CLAIM

The ornamental design for an eye shield, as shown and described.

DESCRIPTION

FIG. 1 is a front view of a first embodiment of an eye shield, showing my new design;

FIG. 2 is a rear view thereof;

FIG. 3 is a bottom view thereof;

FIG. 4 is a front perspective view thereof;

FIG. 5 is a side view thereof;

FIG. 6 is a top view thereof;

FIG. 7 is a front view of a second embodiment of an eye shield;

FIG. 8 is a rear view thereof;

FIG. 9 is a bottom view thereof;

FIG. 10 is a front perspective view thereof;

FIG. 11 is a side view thereof;

FIG. 12 is a top view thereof;

FIG. 13 is a front view of a third embodiment of an eye shield;

FIG. 14 is a rear view thereof;

FIG. 15 is a bottom view thereof;

FIG. 16 is a front perspective view thereof;

FIG. 17 is a side view thereof; and,

FIG. 18 is a top view thereof.
